UNITED STATES PATENT OFFICE

CLARENCE W. PARKE, OF GARLAND, UTAH

TOY STEEPELCHASE

Application filed May 23, 1927. Serial No. 193,552.

This invention relates to amusement devices, and the present device is to provide a novel amusement device in the form of a steeple-chase or racer, constructed on a small scale and providing entertainment simulating a horse race, in which a plurality of figures constructed in the likeness and form of horses may be caused to automatically traverse parallel courses, and the progress of which may be more or less impeded or retarded to provide uncertainty in the outcome of a race.

In carrying out the hereinabove primary object it is contemplated to provide a plurality of such figures having the form of horses or other animals, with movable limbs and bodies, together with means for causing the animation of the figures in simulation of the running and leaping movements of the animal beings which they represent.

It is further contemplated to provide a plurality of parallel courses, each of which is provided with a plurality of hurdles or other obstacles, through which the horses must move and over which they appear to leap, together with means automatically operable for effecting the movement and progress of the figures.

It is a further object to provide means, not synchronized with but adapted to retard the progress of the figures, individually and at irregular intervals, so as to cause variations in the progress of the several figures, thus making it impossible to determine which of the figures will traverse the greatest distance in a predetermined length of time.

It is, of course, an object to provide a simple, efficient and economical amusement device, capable of being constructed in various sizes and with certain modifications within the scope of the appended claims, without departing from the spirit of my invention.

In the accompanying drawings I have shown a preferred form of device, in which:

Fig. 1 is a perspective view of the assembled device, partly broken away;

Fig. 2 is a longitudinal section of the device on line 2—2 of Fig. 4;

Fig. 3 is a transverse section of the same on line 3—3 of Fig. 4;

Fig. 4 is a perspective view of the bottom shelf of the device, showing the operating mechanism;

Fig. 5 is a perspective view, substantially enlarged, of a portion of the same;

Fig. 6 is an enlarged side elevation of one of the figures and supporting means therefor;

Fig. 7 is a perspective view of one of a plurality of transversely movable chains with blocks thereon arranged to interrupt and retard the progress of the racing figures.

In its preferred form, my device is mounted on a table T having a top t and a bottom b formed with a raised central portion b'. Said table may have side and end members 1 and 2, respectively, for enclosing the space between the top and bottom, and legs 3, 3, etc., may also be provided for supporting the operating mechanism at a suitable elevation for use. The bottom b is equipped with a plurality of continuous belts or carriers A, A, etc., each of which operates over a set of flanged pulleys. In the form of device shown I provide a set of six of such pulleys, including five idler pulleys B, B, etc., and a single driving pulley B' for each of the carriers A.

Said pulleys B and B' may be of the same or different size and otherwise differ only in that the driving pulleys B' are provided with rows of peripheral teeth 4, 4, etc., arranged near the upper and lower flanges 5, 5, for engagement with correspondingly formed and spaced apertures 6, 6, etc., near the upper and lower edges of the carriers A.

The carriers may be made of leather or other suitable material, and are adapted to be driven by means of the pulleys B', while they operate over the idler pulleys B, B, etc., for conforming the carriers as nearly as possible to the approximate oval form of a race course. All of the pulleys B', B', etc., are mounted on a common longitudinal line and are supported on a cast metal bracket C, rotatably carrying shafts g, g, etc., which are held in bearings h, h, etc., on the member C.

The shafts g, g, etc., extend downwardly through the bottom b' of the table and carry

worm gears D, D, etc., arranged to mesh with and to be driven by worms E, E, etc. All of said worms are mounted on a single drive shaft F which is journaled as at 7 in bearings formed on and suspended from the bracket C, and the shaft may be connected with an electric motor G by means of a suitable clutch 8. Shafts g, g, etc., are differentially connected with the drive pulleys B', B', etc., by means of clutch devices interposed between the bearings h, h, etc., and said pulleys.

Said couplings may consist of cone clutch members 9 formed on or fixed to the shafts g, g, etc., and engaging correspondingly formed recesses 10 formed in the lower ends of the pulleys B'. The upper ends of the shafts g are provided with nuts 11 and washers 12, while springs 13 are held between the washers 12 and the bottoms of the recesses 14 formed in the upper ends of the pulleys for resiliently holding the pulleys in frictional engagement with the clutch members 9. Thus the pulleys B' are friction driven and the operation of the carriers A may be momentarily suspended, retarded or stopped, as and for the purpose hereinafter described, by reason of the interposition of the clutches.

As shown in Figs. 1 and 6, each of the carriers A is provided with a figure having the form of and representing an animate being, such as a horse as at H. Said figures are arranged to move over the race course centrally formed on the table top t, internally of a fence as at 15 surrounding the course. Each of said figures is carried on a supporting tubular standard 16 which moves in a slot 17 formed in the top t of the table.

These slots 17, 17, etc., are parallel and approximately conform to the carriers A, but they may be more curved than shown in order to form an ellipse or oval course. It is important only that the slots should be positioned above the carriers A, and that the portions 18, 18, etc., thereof should be approximately over the pulleys B, B, etc., and B', B', etc.

The central portions 19 and the portions 20, 20, etc., intermediate the slots 17, 17, etc., may be supported on standards 21, which are threaded at 22 and carry nuts 23 and washers 24 above and below the raised bottom portion b' of the table. The upper ends of the members 21 are provided with flanged members 25 adapted to be attached to the table top t by means of screws or bolts 26 as shown in Fig. 3.

The race course on the top of the table is provided with a plurality of hurdles as at I, I, etc., each composed of a plurality of sections i, i, etc., spaced apart above the slots 17 and arranged in sets, as shown. The supporting members 16 of the figures H move through the slots 17, 17, etc., between the hurdles sections. The tubes 16 are slidably

mounted in sleeves 16' fixedly held in bearings j and j' on holders J which are hingedly mounted therein on arms 30 and 31 of brackets K attached to the carriers A, as shown in Fig. 6.

The members K are provided with flanges 28, 28, which are riveted to the carriers A at 29 and are provided with vertically spaced bearings 30 and 31, in each case, between which central portions 32 of the members J are hingedly carried on vertical pins or rods 33 journaled in the bearings 30 and 31 of the members K. The members J have outwardly extending and vertically spaced arms 34 and 35 which terminate in the bearings j and j', respectively.

The tubes 16' connecting the bearings 21 and 22 of member J are slotted at 36 to receive arms 37 which are pivotally attached at 38 between and to a pair of lugs 39, 39 formed on the central portion 32 of member J. Arms 37 are bent downwardly at 40 and are provided with bifurcated lower portions 41 between the furcations of which, in each case, a roller 42 is pivotally mounted on an axis 43 for engagement with alternate convex and concave corrugations 44 and 45 formed on strips of metal or wood, as at L, L, etc.

One of said strips L is provided for each of the carriers A and rollers 42.

The fore-legs 46 and the hind-legs 47 of the figures H are arranged for connection, as shown in Fig. 6, with a vertically slidable rod 48 which extends downwardly through the tubes 16 and have their lower ends normally resting upon the upper edges of the arms 37, for the purpose of moving the legs 46 and 47 backwardly and forwardly as the rollers 42 travel the corrugated members L, so as to simulate the movements of a running horse or animal.

The upper ends of the tubes 16 are suitably secured to the body 49 of the figures H, while the rods 48 are slidably mounted in one or more brackets 50 attached to the body 49. Rods 48 are connected, respectively, with the fore and hind-legs 46 and 47 by means of bars 51 and 52. Bar 51 is connected at its inner end at 53 with rod 48, and is connected at its forward end at 54 with the upper portion of the fore-leg 46. Said bar is hingedly connected with the body 49 at 55 by means of a pin engaging an elongated slot 56 formed in the bar, while the fore-legs 46 of members H are pivoted at 57, as shown. In a similar manner the bars 52 are pivotally connected at points 58 and 59 with the hind-legs 47 of members H and the rod 48.

Said bars are also connected at 60 to the bodies 49 by means of a pin movably engaging an elongated slot 61 in said bar. The hind-legs 47 are pivoted to the body 49 at 62. Thus the alternate elevation and depression of the bars 48 will effect a corresponding backward and forward movement of the ani-

5 mals' legs 46 and 47 to simulate the running movements of a horse. The downward movement of rods 48 may be limited by means of pins 63 carried in the rod and adapted to engage the upper ends of tubes 16. The downward movement of tubes 16 may be similarly or otherwise limited by means adapted to engage the upper end of sleeve 20, as shown at 63'. Thus the rods 48 will operate prior to 10 tubes 16.

10 Members H may be formed of laminations of cardboard, wood or metal, with the rods 48, legs 46 and 47 and bars 51 and 52 mounted between two spaced laminations, so as to obscure the same from view.

15 The pins 33 which hingedly support the members J on the carriers A are provided at their upper ends with nuts 64 and springs 65 interposed between said nuts and the upper 20 bearings 30 of the members K for normally holding said pins upwardly to the extent of the tension of said springs. The lower ends of the pins 33 are provided with rollers 65 mounted for rotation in a horizontal plane 25 for purposes hereinafter described.

One of the driven shafts *g*, as shown in Fig. 4, may be provided with a pulley 66 which is operably connected with a pulley 67 by means of a belt or chain 68. Pulley 67 30 is fixed to a longitudinal counter-shaft 69 which is journaled in a plurality of bearings 70, 70 and extends longitudinally over the bottom *b* of the table outwardly of the raised portion *b'*. Said shaft 69 serves to operate 35 a pair or more of sprocket wheels 71, 71 connected with similar sprocket wheels 72, 72 transversely aligned therewith, and connected by means of link chains 73, 73. The sprockets 72, 72 are carried on short shafts 40 74, 74 held in pairs of bearings 75, 75. Preferably, one of the sets 73 is provided for each set of hurdles I mounted transversely of the race course, as seen in Fig. 1, each set of hurdles comprising a plurality of sections *i*, and 45 a pair of sets of said sections.

The chains 73 are pivotally connected by means of pins 76, 76, etc., with the central portions of transversely operating blocks M, M, etc., which operate with the chains 73 50 transversely of the table T. Said blocks have recesses 77 for receiving the chains 73 and are provided with laterally formed flanges 78, 78 which engage and move in transversely formed grooves 79, 79 formed in the members *b'* for guiding said blocks in true transverse lines.

The blocks M are also provided with convex central portions 80 which extend substantially above the plane of the corrugations 63 of the members L, as seen in Fig. 6. Thus, as the members H are moved by the carriers A, at or about the time the figures H approach the hurdles I, the rollers 42 connected with the members H must of necessity 65 move over the convex bodies 80 of the blocks

M, thus elevating said rollers 42 and the arms 37 to a greater extent than the corrugations 44 serve to elevate them. In such event the upper edges of the arms 37 engage the lower ends of the tubes 16 and cause the members H to be bodily elevated so as to move above the plane of the upper edges of the hurdles I, or at least to appear to move above said hurdles.

Some, but not necessarily all of the blocks M are provided with one or more upwardly extended pins or lugs 81, of different height or size, if desired, so that during the movement of the blocks M in transverse planes, should the rollers 65 encounter one or more of the pins 81 the particular carrier A to which said roller is attached would necessarily be delayed until the chain 73 had moved sufficiently so that the said roller would clear the pin or pins 81. In such event, the clutch 9 on the shaft *g* of pulley B' for a particular carrier A, would slip until the obstruction had been removed, also the particular figure H which was so obstructed in its movement would be retarded 90 while the other figures possibly progressed in their respective courses.

The idler rollers B for the carriers A are mounted on studs 82 secured to the members *b'* by means of nuts and washers 23 and 24, 95 respectively, as in the case of the standards 21. The central portions 80 of the blocks M project upwardly through and move in transverse slots 83 formed in the member *b'*, while the opposite portions of the chains move under the bottom *b* and upwardly through notches 84, 84, etc., cut in the edges of said members *b*.

The device shown and described may be arranged so that the rollers 65 will normally 105 clear the central portions 80 of the blocks M, and one or more of the units may be arranged so that the rollers 65 connected therewith would engage pins shorter than those engaged by the other figures, for providing a 110 differential of some of the units with respect to the others.

In operation, when the motor G is energized power is communicated to the drive shaft F, through the worms E and gears D to 115 the shaft *h*, frictionally connected with the pulleys B', thus causing the carriers A, A, etc., to move in parallel planes around the course. The transverse chains 73, including the blocks M, M, etc., are operated, as stated, from the drive shaft continuously for impeding the progress of the members H at intermediate points, and for irregular periods of time. The members H are constantly operated to simulate the running of horses, and are intermittently operated to simulate the leaping of such animals for clearing the hurdles I. The operation may continue for a given lapse and may terminate at a given 125 point on the course, as elected.

Due to the fact that the members M are not timed with the carriers A and said members are of different character, it is impossible to predetermine the possible progress of a given one of the members H over the course. The means of mounting the figures H on the carriers A, as shown in Fig. 6, adapts the figures to movement outwardly from the carriers, and the slots 17 in the table top t may be made to conform to the usual oval or ellipse of the race course or substantially so, the pivotal connection of the members J and K serving to accommodate the movement of the members H in courses of different curvature and the carriers A must necessarily follow because of the arrangement for operably supporting them as shown.

The slot 17 in the member t may be made very narrow by providing the supporting tube 16 of rectangular cross section, instead of round as shown, and the arrangement of the member J should be such that the arm 37 will move upwardly for a distance sufficient to elevate the figures H as they move over the hurdles I.

The forelegs 46 of the figures H may be jointed as at 46' and arranged in such a manner that the legs will bend at the knees when the figures are simulating the running movements of a horse, though this is not material to my invention. It will also be understood that the connections of the fore and hind-legs 46 and 47, respectively, with the operating rod 48 may be arranged in any suitable manner, and different from that shown in the drawings, for the purpose of providing sufficient movement to the legs and for effecting the proper articulation of the legs in simulation of the running movements of a horse.

40 What I claim is:

1. A steeple chase comprising an endless flexible carrier, means for operating the same, a figure operatively held thereon and arranged for movement over a given course thereby, and means associated with said carrier for animating said figure during the movement thereof to simulate the limb movements of the animate being of which said figure is a likeness.

50 2. A steeple chase comprising a power driven flexible carrier, a figure reciprocably mounted on and arranged for movement with said carrier and representative of an animate being, means adjacent said carrier for animating the figure in simulation of the animate being of which the same is a likeness, during the continued movement of said carrier, and means associated with said animating means for intermittently reciprocating said figures.

55 3. A steeple chase comprising a plurality of flexible carriers, means for operating the same in parallel courses, figures carried thereon and movable thereby and formed in the likeness of animate beings, said figures

having movable limbs, and means adjacent the carrier for operating said figures bodily and for articulating the limbs thereof in simulation of the beings of which they are the likeness.

4. A steeple chase comprising a continuous flexible carrier, figures reciprocably mounted thereon representative of an animate being and having limbs arranged for articulation, a track over which said figures are movably disposed, and means including members engaging said track for articulating said limbs during the movement of said figure over a given course, to simulate the running movement of the animate being represented by said figure, and means associated with said track for reciprocating the figure during the movement of the carrier.

5. A steeple chase comprising a continuous flexible carrier, a figure reciprocably mounted thereon representative of an animate being and having limbs arranged for articulation, a track, and means including members engaging said track for articulating said limbs during the movement of said figure over a given course, to simulate the running movement of the animate being represented by said figure, and means associated with said track and for operating said track engaging members or intermittently elevating said figure beyond a normal plane of movement for simulating the leaping movements of an animate being.

6. A steeple chase comprising a continuous carrier, driving means differentially connected therewith, an articulated figure representing an animal operably supported on said carrier for movement in a given course, means including a track and members engaged therewith for articulating said figure to simulate the running movements of an animal during the movement of said carrier, and means intermittently operable during the movement of said carrier and adapted for operative association with said animating means for retarding the progress of said figure.

7. A steeple chase comprising a plurality of continuous carriers, driving means differentially connected therewith, figures operably supported on said carriers, a course defining the movements of said figures, a track paralleling said course, animating means associated with said track for effecting the movements of said figures to simulate the running movements of an animal represented thereby, and means associated with the track and adapted to be engaged by said animating means for momentarily interrupting the progress of said figure at regular intervals.

8. A steeple chase comprising a plurality of continuous carriers, means differentially connected therewith, to permit the retardation of the carriers, selectively, figures operably supported on said carriers, a course defining the movements of said figures, means

including a track and members movable thereover for animating said figures to simulate the running movements of an animal represented thereby, and means associated with said track and engaged by the animating means for additionally moving said figures at intervals to simulate the leaping movements of an animal.

9. A steeple chase comprising a plurality of continuous flexible carriers, means differentially connected therewith, permitting the retardation of the members selectively supported on said carriers, a course defining the movements of said figures, means includ-

10 15 ing a track and members movable thereover for bodily reciprocating and animating said figures to simulate the running movements of an animal represented thereby, and means disposed in the paths of said animating means 20 for momentarily retarding the same to permit one or more of the figures to progress faster than the others.

10 25 30 35 40 45 50 55 60 65 70 75 80 85 90 95 100 105 110 115 120 125 A steeple chase comprising a table having a race course thereon, a plurality of flexible carriers operably mounted below said course, figures mounted for operation above said course and operably connected with said carriers, a track, animating means including members engaging said track for operating said figures to simulate the running movements of an animal, means disposed in the path of said animating members for intermittently elevating said figures to simulate the leaping movements of an animal, and means operable in planes transverse to the movement of said figures and engaged by said animating members, arranged to interrupt and retard the progress of said figures at intervals, as described.

11. A steeple chase comprising a supporting member having a race course on the top thereof, a plurality of parallel carriers mounted below said course, a driving mechanism differently connected with said carriers for permitting the retardation thereof, figures mounted for movement around said course and arranged for operation to simulate the running and leaping movements of an animal, and independent means connected with said figures for effecting said running and leaping operations, as described.

12. A steeple chase comprising a table having spaced bottom and top portions, an endless flexible carrier operatively mounted between said top and bottom portions, said top having an endless slot therein, above said carrier, a corrugated track on said bottom below said carrier, a figure movably disposed above said top and provided with movable limbs, means mounted on said carrier connected with the body and the limbs of said figure and with said track for reciprocating the body and moving the limbs thereof during the operation of said carrier.

13. A steeple chase comprising a table hav-

ing spaced bottom and top portions, an endless flexible carrier operatively mounted between said top and bottom portions, said top having an endless slot therein above said carrier, a corrugated track on said bottom below said carrier, a figure movably disposed above said top and provided with movable limbs, means mounted on said carrier connected with the body and the limbs of said figure and with said track for reciprocating the body and moving the limbs thereof during the operation of said carrier, and means associated with the track for interrupting and retarding said figure as described.

14. A steeple chase comprising an endless flexible carrier, a bracket fixed thereto, a supporting member carried on said bracket, a pair of telescoping members reciprocably mounted on said supporting member, a figure comprising a body and limbs connected respectively with said reciprocable members, a track disposed below said carrier and means engaging said track and said reciprocable members for respectively reciprocating said figure bodily and articulating the limbs thereof for the purpose described.

15. A steeple chase comprising an endless flexible carrier, a bracket fixed thereto, a supporting member carried on said bracket, a pair of telescoping members reciprocably mounted on said supporting member, a figure comprising a body and limbs connected respectively with said reciprocable members, a track disposed below said carrier and means engaging said track and said reciprocable members for respectively reciprocating said figure bodily and articulating the limbs thereof for the purpose described and means associated with said track and effective at irregular intervals for retarding the movement of said carrier of said figure.

16. A steeple chase comprising a plurality of endless flexible carriers arranged in parallelism, means for operatively supporting said carrier in spaced relation to each other, a differential drive mechanism connected with said carriers, a table having a top with a race course thereon and slots therein above said carriers, figures yieldably supported on said carriers and disposed above said top, said figures having a body and limbs, independent means for supporting the body and limbs on the carriers, means for intermittently reciprocating the bodies of said figures and for articulating the limbs thereof during the movement of said carrier, and means for irregularly retarding the movement of the carriers for effecting the movement of said figures so as to simulate a race over said course.
